US00D732027S

(12) **United States Design Patent**
Cazalet et al.

(10) **Patent No.:** US D732,027 S
(45) **Date of Patent:** ** Jun. 16, 2015

(54) **REMOVABLY ATTACHABLE LENS**

(71) Applicant: **Google Inc.**, Mountain View, CA (US)

(72) Inventors: **Peter Michael Cazalet**, Campbell, CA (US); **Matthew Wyatt Martin**, Ross, CA (US); **Maj Isabelle Olsson**, San Francisco, CA (US)

(73) Assignee: **Google Inc.**, Mountain View, CA (US)

(***) Term: **14 Years**

(21) Appl. No.: **29/510,270**

(22) Filed: **Nov. 26, 2014**

(57) **CLAIM**

The ornamental design for a removably attachable lens, as shown and described.

DESCRIPTION

FIG. 1 is a front perspective view of a removably attachable lens according to our design;

FIG. 2 is a front elevation view of the removably attachable lens of FIG. 1;

FIG. 3 is a back elevation view of the removably attachable lens of FIG. 1;

FIG. 4 is a right elevation view of the removably attachable lens of FIG. 1;

FIG. 5 is a left elevation view of the removably attachable lens of FIG. 1;

FIG. 6 is a top elevation view of the removably attachable lens of FIG. 1;

FIG. 7 is a bottom elevation view of the removably attachable lens of FIG. 1; and,

FIG. 8 is a rear perspective view of the removably attachable lens of FIG. 1 showing additional environmental features that can be associated therewith.

Broken lines in the drawings depict unclaimed environment only and form no part of the claimed design.

Dash-dot lines adjacent unshaded areas represent boundaries of the claimed design and form no part of the claim.

1 Claim, 5 Drawing Sheets
